LOUVER VENTILATOR

Harry O. Nelson, Miami Beach, Fla.

Application October 11, 1938, Serial No. 234,468

5 Claims. (Cl. 189—69)

The invention relates to improvements in louver ventilators and the primary object is to devise a transparent louver ventilating window which will provide ventilation and light while giving protection against burglars and the elements.

Another object of the invention resides in the provision of a louver ventilator wherein the louvers are so arranged as to not require attention except in extreme weather conditions.

A further object of the invention is to provide a screened louver ventilator so constructed that the louvers may be adjusted without interference by the screen.

Yet another object is to provide a louver ventilator having alternately arranged stationary and pivoted louvers.

A still further object of the invention resides in the provision of a transparent louver ventilating window which is architecturally attractive.

Another object is to provide a glass louver ventilating window so constructed as to facilitate the replacement of broken louvers.

Another important object of the invention is to devise a louver ventilator mounted in a stationary frame for disposition in a wall opening.

A further important object of the invention is to provide a louver ventilator mounted in a sash for installation in a framed wall opening.

An additional object of the invention resides in the provision of a louver ventilator for attachment to a frame-supported sash.

A further object is to provide louver ventilator constructions for use in new work or as improvements to existing structures, and in conjunction with casement or other types of windows, whether of metal or wood.

Other objects and advantages of the invention will become apparent during the course of the following detailed description, taken in connection with the accompanying drawings, forming a part of this specification, and in which drawings—

Figure 1 is an exterior view in elevation of a preferred form of my adjustable glass louver window and which I term an "attachment to standard window sash," the same being shown applied to a frame-supported sash.

Figure 2 is an interior view in elevation of the window illustrated in Figure 1.

Figure 3 is a horizontal sectional view substantially on the line 3—3 of Figure 2.

Figure 4 is a vertical sectional view of the window with the louvers open.

Figure 5 is a view similar to Figure 4 but showing the louvers closed.

Figures 6, 7, 8 and 9 are perspective views of louver holders preferably forming a part of the invention.

Figure 10 is a sub-assembly view in vertical section of a louver holding member preferably forming a part of the invention.

Figure 11 is a perspective view of the louver tilting member.

Figure 12 is a vertical sectional view of a modified form of my adjustable glass louver window as attached to a frame-supported window sash.

Figure 13 is an interview view in elevation of a different form of my adjustable glass louver window, and which I term a "sash attachment to standard window frame," the same being shown in association with a window frame.

Figure 14 is a fragmentary horizontal sectional view substantially on the line 14—14 of Figure 13.

Figure 15 is a vertical sectional view of the window construction illustrated in Figure 13.

Figure 16 is an interior view in elevation of a different form of my adjustable glass louver window, and which I term a "stationary unit."

Figure 17 is a fragmentary horizontal sectional view substantially on the line 17—17 of Figure 16.

Figure 18 is a vertical sectional view of the stationary unit and showing its application to a wall opening.

In the drawings, which show preferred and modified forms of the invention, and wherein similar reference characters denote corresponding parts throughout the several views, the letter A designates a standard window frame; B a standard window sash; C an attachment to the sash B; C' a different attachment to the sash B; D a sash attachment to the frame A; while E designates a stationary unit for mounting in a wall opening.

The frame A and sash B may be of any suitable cross-sectional shape and of any suitable material and the sash B, when employed, may be hung in any desired manner for opening and closing movement relative to the frame A. In the examples shown, the material employed is metal and the sash are of the outwardly swinging casement type. The frame A may include the usual asymmetrically flanged bars or beams 25 for the jamb, head, and sill portions, and providing inner and outer flanges 26—27 and a connecting web 28. The frame A may be of the multiple window type, as shown, wherein the usual symmetrically flanged bar or beam 29 is utilized at the meeting stile, and providing inner and outer flanges 30—31 and a connecting web 32. Secured inwardly of the marginal edges of the inner flanges 26 and 30 which define each window opening is a conventional screen 33 including a border frame 34.

Referring particularly to the forms of invention illustrated in Figures 1-12, the sash B preferably is formed of asymmetrically flanged bars or beams 35 providing inner and outer flanges 60

36—37 and a connecting web 38. Pivots securing the sash B for outward swinging movement relative to the frame A are the usual extension hinges 39. Secured to the inner flange 5 26 at the sill portion of the frame A, is a suitable casement operator 40 including the usual lever 41 extending beneath the screen for co-action with the inner and outer flanges of the sash B. The usual glass and muntins (not shown) are 10 removed from the sash B to provide a clear opening for the accommodation of the attachment C or C'.

Referring first to the attachment C, the same 15 comprises a pair of hollow side members 42 each including a channel bar 43 and a closure plate 44 secured in abutment with the inner and outer flanges 45—46 of the channel bar, as by screws 47, the outer flange 46 including a marginal edge portion 48 extending beyond the closure plate 44. The attachment C also comprises a hollow 20 head 49 of polygonal shape in cross-section and including a downwardly and outwardly inclined wall 50 and an inwardly extending flange 51 having a depending skirt 52. The attachment C 25 further comprises a sill 53 including an upwardly and inwardly tapered flange 54 and a downwardly and outwardly inclined apron 55. The head, sill and side channels are drilled to provide openings 56 to facilitate attachment to the sash B, as by cap screws 57.

Riveted or otherwise secured to the closure 30 plates 44 are stationary louver holders 58 including flanges 59 cut away intermediate their ends to provide notches 60. A web 61 is provided to close the lower end 62 of each holder 58, the upper end 63 being open. Secured to opposite flanges 59 and projecting laterally therefrom at opposite ends of the holders are arcuate leaf springs 64. Pivots secured to the closure 35 plates, as by pins 65, are swinging or tilting louver holders 66, each including a closed lower end 67 provided with a lateral opening 68, and a truncated or obliquely terminating open upper end 69. These louver holders 58 and 66 40 are disposed in alternate relation to one another intermediate the ends of the closure plates 44. Pivots secured to the lower end portions 45 of the closure plates are holders 66', relatively shorter than the holders 66, but otherwise having 50 the same characteristics. Secured to the upper end portion of each closure plate 44 is a holder 70 including a lower section 71 pivoted to the plate at its closed lower end 72, as by a pin 73, the holder further including an upper section 55 74 of angular shape in cross section and including a flange 75 securable as by screw 76 to the head 49, in a manner whereby the companion flange 77 is disposed in spaced parallel relation to the inclined wall 50.

60 The louvers 78 carried by the stationary and tilting holders 59 and 66 are of a width greater than that of the louvers 79 carried by the holders 66' and 70. Preferably all the louvers are formed of a transparent material, such as glass. 65 It will be noted that unauthorized removal of the louvers from the outside of the window is practically impossible even tho the louvers are disposed in parallel or open position due to interference of the screen with lifting of the louvers 70 from the holders. As the screen is readily detachable from the inside of the window, any of the louvers except that carried by the upper holders 70 may be lifted out for cleaning or replacement. The uppermost louver may be removed by withdrawing the screws 76 and de-

taching the angular holder sections 74, whereby the lower holder section 71 will swing inwardly to permit clearance of the upper louver past the head flange and skirt 52, as it is lifted out of the holder. 5

Means is provided to control the pivotal relation of the tiltable louvers relative to the stationary louvers. Disposed within the hollow side member 42 preferably at the hinge side of the sash B, is an elongate member 80 provided with 10 longitudinally spaced pins 81 projecting from the inner side 82 thereof. Projecting from the opposite side of the member 80 is a pin 83, which may constitute an extension of one of the pins 81. Formed in the plate 44 which encloses the 15 member 80 is a plurality of arcuate slots 84 coaxial with the pivot pins 65 and through these slots the pins 81 extend for connection with the pivotal louvers, as by projection of the pins into 20 openings 85 provided adjacent the upper ends of the pivotal louver holders. Extending through arcuate slots 86—87, shown in Figure 3 of the drawings, is the pin 83 which terminates between 25 the sash B and frame A when the sash is in its closed position.

Secured to the inner flange 26 of the frame A, and outwardly of the screen frame 34 is a control lever 88 including a handle portion 89 and a swingable arm 90 adapted to engage the pin 83 when the sash is in closed relation to the frame A. Threaded on the fulcrum pin 91 of the control lever is a wing nut 92 for releasably securing the lever in any desired position. 30

In the attachment C the springs 64 carried by 35 the stationary holders are of a length and accuracy to constantly remain in contact with the sides of adjacent pivoted holders. The attachment C' is identical in every respect with the attachment C except that the stationary louver holders there-of are provided with arcuate springs 64' which 40 contact the sides of adjacent pivoted holders only when the pivoted louvers are closed or about to close.

To the apron 55 is secured, as by riveting, an 45 elongate transversely arched resilient strip 93 having a beaded marginal free edge 94 constantly contacting the outer surface of the lowermost louver 79. This strip 93 provides additional protection against the weather.

By depressing the handle 89, the arm 90 will 50 swing outwardly and, through engagement with the pin 83, the member 80 will carry the pins 81 along the arcuate slots 84, whereby to tilt the swingable louvers toward the stationary louvers, the opposite marginal edges of the tiltable louvers 55 when closed being accommodated in the notches 60 of the stationary louvers 58, or between the sections 71 and 74 of the stationary louvers 70, as the case may be.

By releasing the handle, the louvers will 60 return to open position, due to the weight of the elongate member 80. The springs 64 of the attachment C will also assist in returning the louvers to open position.

With this arrangement, it is not necessary to 65 provide a positive connection between the operating lever 88 and the louver tilting member 80, such as would interfere with movement of the sash B relative to the frame A.

With my sash attachment D, the sash B is 70 eliminated and connection is made directly to the frame A, as by suitable hinges 100 including removable pintles 101 and leaf sections 102 which may be secured as by rivets 103.

It will be noted that the sash attachment D is 75

provided with a head section 104, a sill section 105 and side sections 106, having cross-sectional shapes which are substantially similar to the respective combined cross-sectional areas of the

5 head, sill and jamb sections of the attachment C plus the sash B. For example, the inclined wall 107 of the head 104 is similar to the wall 50 of the previously described attachment C, and the apron 108 of the sill section 105 is similar to and 10 functions in the same manner as the apron 55 of the attachment C. The louver arrangement is identical in the attachments C and D and the parts thereof bear like reference characters.

Housed within the side section 106 preferably 15 adjacent the hinges, is a louver tilting member 80 having pins 81 operating through slots 109 in side plates 110, the pin 83 extending through a slot 111 in the side section 106 to a point between the side section and the frame A. The 20 control lever 88 is disposed on the frame A and includes a swinging arm 90 extending between the frame A and sash attachment D for coaction with the louver tilting member 80 in a manner similar to that described in connection with the 25 attachment C.

As for my stationary unit E, shown in Figures 16-18 of the drawings, the same embodies a hollow frame 112 which is adapted for mounting in a wall opening 113. The head section 114 includes an inclined wall 115 and the sill section 116 includes an inclined wall 117 constituting an apron.

Multiple ventilator units E may be provided, if desired. In the example shown, the meeting stile 35 118 between the multiple units houses individual louver tilting members 80 which are independently actuated through separate control levers 88. The tilting members 80 are of course provided with pins 81 co-acting with pivoted holders 40 responding to the holders 66-66', of the previously described attachments C and D. Openings 119 preferably are provided in opposite sides of the frame 112 and these openings are covered with plates 120 similar to the plates 44. If desired, the meeting stile 118 may include fins 121 provided with slots 122 in which the pins 83 are disposed. The angular retainer 123 for the uppermost louver is relatively short and includes a laterally offset tab portion 124 removably secured 45 to the head section as by screws 125.

From the foregoing it will be seen that I have provided improved forms of adjustable glass louver ventilators embodying generic features of construction and which ventilators may be employed as attachments to existing standard structures or in new work.

Various changes may be made in the forms of invention herein shown and described, without departing from the spirit of the invention or 50 the scope of the following claims.

I claim:

1. A ventilator comprising a frame, a plurality of spaced parallel louver panels fixed transversely within the frame, a plurality of louver slats disposed transversely within the frame and in alternate spaced relation to said panels, means securing said slats for pivotal movement about axes transversely of the frame and intermediate opposite portions of said slats, whereby said opposite 70 portions at their free marginal edges may swing

into and out of engaging relation with said panels, and resilient means carried by said panels and urging the opposite portions of said slats away from engaging relation with said panels.

2. In a ventilator, a frame including opposite 5 sides and a sill member, a louver member extending transversely between said sides and superjacent said sill member, means pivotally securing said louver member for swinging movement about an axis intersecting said sides, a resilient strip 10 extending between said sides and in overlapping relation to said louver member and sill member, and means securing said strip along a marginal side portion thereof to one of said members, in transversely tensioned relation so that said strip 15 along its opposite marginal side portion will contact the other of said members.

3. In a ventilator, a frame including opposite 20 sides and a sill member, a louver member extending transversely between said sides and superjacent said sill member, means pivotally securing said louver member for swinging movement about an axis intersecting said sides, a resilient strip 25 extending between said sides and in overlapping relation to said louver member and sill member, and means securing said strip along a marginal side portion thereof to said sill member, in transversely tensioned relation so that said strip along its opposite marginal side portion will contact 30 said louver member.

4. In a ventilator, a frame including opposite 35 side members and a head member, said head member being shaped to provide a pair of plane surfaces forming a re-entrant dihedral angle in the lower side of the head member, a pair of holders each including a mouth end portion, said holders being disposed one adjacent each of said side members, a louver panel having opposite end portions slidable into and out of said holders through the mouth end portions thereof, means 40 pivotally securing said holders for swinging movement about an axis intersecting said side members and in a manner whereby said louver panel, upon positioning of its end portions within said holders, may be swung to an angular position 45 within the confines of said dihedral angle and in which position said panel is limited against sliding movement out of said holders through the mouth end portions thereof, and means securing 50 said louver panel in said angular position.

5. In a ventilator, a frame including spaced 55 sides, a plurality of channel-shaped holders having spaced flanges provided with notches intermediate their ends, a plurality of louvers each including opposite end portions, said end portions being positioned between said flanges, means securing the holders to the sides of the frame so as to support said louvers in spaced parallel relation transversely of the frame, a plurality of slats disposed in alternate relation to said louvers, and means securing the slats for pivotal movement about axes transversely of said frame sides, said slats including marginal side edges swingable into and out of contact with the adjacent alternate 65 louvers, said marginal side edges, at the opposite end portions of said slats, being disposed within the notches of said louver holder flanges.
